UNITED STATES PATENT OFFICE.

ANTON A. STAVICK, OF SIOUX CITY, IOWA.

SHOE-SHINING MACHINE.

Application filed May 24, 1922. Serial No. 563,335.

To all whom it may concern:

Be it known that I, ANTON A. STAVICK, a citizen of the United States, and a resident of Sioux City, in the county of Woodbury 5 and State of Iowa, have invented a new and useful Shoe-Shining Machine, of which the following is a full, clear, and exact description.

My invention relates to improvements in 10 shoe shining machines, and particularly that type of machine which is intended for manual operation.

An object of my invention is to provide a shoe shining machine of the type described 15 in which means is provided for distributing polishing fluid over the shoe, and in which means is provided for polishing the shoe subsequent to the distribution of polishing fluid.

20 A further object of my invention is to provide a shoe shining machine of the type described that is simple in construction and efficient in operation.

Other objects and advantages will appear 25 in the following specification, and the novel features of the invention will be particularly pointed out in the appended claims.

My invention is illustrated in the accompanying drawings, forming part of this application, in which—

Figure 1 is a top plan view of an embodiment of my invention,

Figure 2 is a side elevation of the mechanism illustrated in Figure 1,

35 Figure 3 is an enlarged side elevation of a part of the mechanism illustrated in Figure 1,

Figure 4 is an enlarged side elevation of 40 a portion of the mechanism illustrated in Figure 1,

Figure 5 is an enlarged rear elevation of 45 a part of the mechanism illustrated in Figure 1,

Figure 6 is an enlarged fragmentary view 50 of a part of the mechanism illustrated in Figure 1, and

Figure 7 is an enlarged top plan view of 55 the mechanism illustrated in Figure 1.

In carrying out my invention I provide a 60 base member A having an upright rectangular frame B supported thereupon adjacent the rearward end. The frame B is provided with a top wall B', (see Figure 1). A sole plate 1 is secured to the top wall B' of the 65 frame B so that the sole of the shoe may rest thereupon.

A heel plate 2 is fixed to the upper end of an arcuate lever 3 projected through the top wall B' of the frame B, and fixed at its lowermost end 3^a to a shaft 4, rotatably mounted on the frame B. Downward movement of the heel plate 2 as by pressure of the heel thereupon will occasion the rotation of the shaft 4.

A torsion spring 5 is provided for normally maintaining the lever 3 in such a position as to normally elevate the heel plate 2. One end of the shaft 4 is provided with a radially extending arm 6 having an eye portion 6^a at the outermost end thereof. A connecting rod 7 is pivotally connected to the arm 6 at 6^a and has its opposite end pivotally connected at 7^c with a crank arm 8 extending radially from one end 8^a of a crank shaft 9 which is pivotally mounted upon uprights 10. The axis of the crank shaft 9 is in substantial parallel relation with the axis of the shaft 4; hence oscillation of the shaft 4 will occasion oscillation of the crank shaft 75

9. A pair of arms 11 are pivotally connected 80 at H to the crank shaft 9 and a torsion spring 12 disposed concentric with the crank shaft 9 between the arms 11 is provided for yieldably forcing the arms 11 downwardly toward the top B' of the frame B. Each of 85 the arms 11 is provided with a pair of fore arms 11^f slidably mounted thereupon by means of connecting members 11^c. The fore arms 11^f are provided with depending portions 16. A compression spring 16^b is disposed concentric with the fore arms 11^f between the connecting member 11^c and the depending part 16 of the fore arms, so that 90

the fore arms are yieldably drawn toward the crank shaft 9, (see Figure 3). A pair 95 of lifting levers 17 is provided on the fore arms 11^f at the rear of the rearmost connecting member 11^c. These lifting arms extend toward one another when the depending portions 16 of the fore arms 11^f are in a substantially vertical position, as shown in Figure 2. The lifting levers 17 are securely

fixed against movement upon the fore arms 11^f by means of a clamp 17^k. A tension spring 14 is connected between the arms 11 105 and thereby tends to draw the arms 11 toward one another to prevent the arms from normally spreading away from one another.

A member which I choose to call a tilting cam 32 is mounted upon the under side of the top wall B' of the frame B and ar-

ranged to extend beyond the front edge of the top wall as shown in Figure 1. The particular construction of this tilting cam is shown in Figure 7, and has a V-shaped portion V formed therein with which the depending portions 16 of the fore arms 11^f may engage in such a manner as to draw the depending portions 16 toward one another and hence rotate the fore arms 11^f. The extreme rearward end of the fore arms 11^f are provided with a hook member 22. Brushes 20 having two sets of bristles on two sides thereof are mounted concentric with the fore arms and are provided with openings in the end walls thereof for receiving the remote end of the hook-shaped members 22, thereby preventing rotation of the brushes 20 and permitting the reversal of the brushes 20 so that the uppermost bristles may face downwardly by turning the brush 20 180° upon its support on the fore arm. Compression springs 19 are mounted concentric with the fore arms 11^f between the brushes 20, and fixed collars 18 are carried by the fore arms, thereby forcing the brushes 20 toward the hook members 22 and in engagement therewith. A pair of upright standards 23^v are carried by the frame B adjacent the forward end of the frame and extend beyond the upper wall B' of the frame. The upper ends of these standards have the shape of an open eye 23, (see Figure 6). A crank shaft 24 (see Figure 5) is rotatably mounted in the eye-shaped bearing members 23 of the standards 23^v. A roller 26 is rotatably mounted upon the crank shaft 24. This roller I choose to call a wicker roller. A trough 27 is suspended upon the crank shaft 24 so as to partially encompass the roller 26, whereby liquid in the trough 27 may be taken up by the roller 26 as it is rotated. The trough 27 remains in an upright position by virtue of its own weight. A crank handle 25 forms a part of the crank shaft 24 by means of which the crank shaft 24 may be rotated to move the portion of the crank shaft containing the roller 26 and the trough 27 above the brushes 20 at will. Normally the brushes 20 pass over the wicker roller 26 and are provided with polishing fluid which is contained in the trough 27 so that the brushes may carry the polishing fluid which is contained in the trough on toward the shoe resting upon the sole plate 1, and the heel plate 2, as the crank shaft oscillates. A pair of uprights 29 are also provided upon the frame B and extend upwardly therefrom adjacent the forward end of the sole plate 1. A lifting crank 28 is pivotally mounted upon the uprights 29 and is for the purpose of engaging with the lifting levers 17, (see Figure 1 dotted lines) whereby the arms 11 and fore arms 11^f may be lifted in the man-

ner hereinafter described. One end of the lifting crank shaft 28 is provided with a V-shaped member 30 having a hook portion 32 at its outermost end by means of which the lifting crank shaft may be held in a predetermined position by the engagement of the hook-shaped member 32 with the adjacent upright 29. A second hook portion 32^a adjacent to the hook portion 32 is provided for still further adjustment of the position of the lifting crank shaft 28. A brush resting rod 21 extends across the top wall B' of the frame B immediately in front of the brushes 20 when the brushes are at rest as shown in Figure 1, and is for the purpose of supporting the brushes out of engagement with the top wall B' of the frame B when the device is not in use.

A stationary brush 31 is supported upon the frame B, immediately at the rear of the heel plate 2 so that movement of the heel of the shoe, as in actuation of the plate 2, may serve to remove dust and the like from the heel by contact with the brush 31, which will also polish the heel.

From the foregoing description of the various parts of the device, the operation thereof may be readily understood. In operating my improved shoe shining device, it is first necessary to provide a polishing liquid in the trough 27 and to make sure that the trough 27 with its wicker roller 26 is in the position shown in Figure 2. The lifting crank shaft 28 should be in the position shown in Figure 1. The person wearing the shoe which it is desired to polish will place the shoe so that the sole thereof rests upon the sole plate 1 beneath the lifting crank shaft 28. The heel will rest upon the heel plate 2. Downward pressure upon the heel plate 2 by the heel will occasion rotation of the shaft 4 against the action of the spring 5, and hence oscillation of the crank shaft 9 to which the shaft 4 is connected in the manner set forth. The crank shaft 9 will move upwardly as shown in Figure 1 toward the position shown in dotted lines. As the crank shaft 9 moves upwardly on the first cycle of its oscillatory movement, the arms 11 will be projected toward the shoe. The brushes 20 will pass over the wicker roller 26 and gather polishing fluid thereupon. Further movement of the crank shaft 9 will occasion still further movement of the arms 11 with their fore arms 11^f so that the brushes will engage with the vamp of the shoe. The polishing fluid will thereby be distributed on the vamp of the shoe and the brushes will continue in their movement toward the heel of the shoe. At this time the depending portions 16 of the fore arms 11^f will engage with the cam rod 32 to be drawn toward one another, thereby causing the partial rotation of the fore arms 11^f. The lifting levers 17 will

assume the position shown in Fig. 3, and the outer ends thereof will engage with the lifting rod 28, as shown in Figure 1, i. e., the lifting levers 17 will lie with their outermost ends above the lifting rod 28 and engaged with the upper side thereof. Still further movement of the crank shaft 9 will cause the fore arms 11^t and the arms 11 to move against the action of the torsion spring 12 and therefore lift the brushes 20 upwardly upon the shoe. In shining oxford shoes, the lifting rod 28 is moved so that the lifting lever 17 may not engage therewith to move the brushes.

15 The spring 5 will tend to restore the crank shaft 9 to its original position when pressure is relieved at the heel plate 2, thereby completing the last portion of the oscillatory cycle.

20 Repeated movement of the heel plate 2 downwardly and up will serve to thoroughly distribute the polishing liquid upon the shoe and when it is desired to polish the shoe the crank shaft 24 is rotated by means of the 25 handle portion 25 so as to cause the wicker roller 26 to be lifted out of engagement with the brushes 20.

Movement of the heel relative to the brush 31 will serve to adequately clean and polish 30 the heel portion of the shoe.

I claim:

1. A shoe shining machine of the character described comprising a fixed sole plate for supporting the sole of a shoe, a movable 35 heel plate for supporting the heel of said shoe, a pair of brushes, means for moving said brushes longitudinally of said sole plate, and consequently upon said shoe, means associated with said heel plate for actuating 40 said brush operating means, and means for supplying polish to said brushes prior to their movement upon said shoe, said last named means being arranged for movement out of registration with said brushes at will.

2. A shoe shining machine of the character described comprising a fixed sole plate, a movable heel plate, a crank shaft, means associated with said heel plate and said crank shaft for causing the oscillation of said crank shaft when said heel plate is reciprocated, a pair of arms connected at one end with said crank shaft, and having brushes supported at the opposite ends, a lifting rod disposed over said sole plate, a pair of lifting levers carried by said arms, and normally out of registration with said lifting rod, and means associated with said lifting levers for rotating said lifting levers when said arms are moved toward said sole plate, whereby said lifting levers may engage with said lifting rod and elevate said brushes.

3. A shoe shining machine of the character described comprising a fixed sole plate, a movable heel plate, a crank shaft, means associated with said heel plate and said crank shaft for causing the oscillation of said crank shaft when said heel plate is reciprocated, a pair of arms connected at end with said crank shaft and having brushes supported at the opposite ends, a lifting rod disposed over said sole plate, a pair of lifting levers carried by said arms and normally out of registration with said lifting rod, a pair of depending members associated with 75 said lifting levers, and a cam disposed a predetermined distance from said sole plate for engaging with said depending members to cause the rotation of said lifting levers upwardly, whereby said lifting levers may 80 engage with the lifting rod to elevate said brushes.

Signed this 22nd day of May, A. D. 1922.
